UNITED STATES PATENT OFFICE.

ERASMUS BENNETT, OF CLARKSVILLE, NEW YORK

IMPROVEMENT IN WAGON-BRAKES.

Specification forming part of Letters Patent No. 41,595, dated February 16, 1864.

To all whom it may concern:

Be it known that I, ERASMUS BENNETT, of Clarksville, in the county of Albany and State of New York, have invented a new and useful improvement in the construction of wagon-brakes, by means of which said brakes can be applied to an ordinary pole without materially changing the construction, while at the same time all the moving parts are accessible; and for simplicity and durability the advantages over others will be clearly set forth in the following specification.

The nature of my invention consists in applying to an ordinary pole of a wagon two hounds, situated one on each side of the same. Said hounds slide with the pole backward and forward between two other hounds, which are secured to the forward axle-tree of the wagon. The sliding hounds and pole are provided with an elongated slot in each, through which a bolt passes, which is firmly secured to the outer or fixed hounds. A plate is secured to the upper side of the pole, on which an upright bolt is forged. Two arms provided with eyes fit on the upright bolt and are kept in place by a nut on the top of same. Each arm plays freely through an eye or staple secured to each stationary hound. The outer end of each arm has an eye to receive a side rod, the other end of which is secured to the cross brake-bar. The great advantage in this arrangement is that the arms and staples are all on the upper side of the pole and hounds, and can be easily taken apart and put together from above instead of being placed underneath, as in other arrangements, where they are out of sight, exposed to clogging with mud in the joints, and almost impossible to get at when out of order.

The brakes or rubbers are of a peculiar construction and are provided with a flat projection on the back end of each, which forms a very convenient step to get in and out of the wagon, and also serves to keep the brake blocks or rubbers in their proper positions so as to bear against the wheels when required.

The hounds, which are secured to the pole, serve to strengthen it materially, and it has no chance to tip sidewise, as the bearings are so wide. An elongated slot is made in the pole and sliding hounds, through which the

draft-bolt passes, which is firmly secured to the stationary or fixed hounds.

When the wagon is not loaded, there is hardly any necessity for the brakes, and they can be easily prevented from coming in contact with the wheels by means of an eyebolt or pin inserted before the draft-pin, thereby preventing the pole and hounds from moving backward, and keeping the brakes or rubbers out of contact with the wheels. To remove the arms and side rods altogether from the pole, it is only necessary to take off the nut on the upright bolt secured to said pole.

I have tested my improvement and it works well, and can be applied with less cost than others in use, as nearly all the old work in a wagon, can be used with advantage.

Having thus set forth the nature of my invention, and to enable others skilled in the art to make and use the same, I will now proceed to describe it, and certify that the accompanying drawings are a full and correct representation of the same, like letters conforming with like parts.

Figure 1 represents a perspective view of a wagon with the brakes or rubbers applied. Fig. 2 is a plan of the same. Fig. 3 is an enlarged view of the brakes or rubbers pressed against the wheel.

A represents the pole; B and C, the sliding hounds secured one on each side of the same; D and E, the stationary or fixed hounds secured to the axle-tree F in the usual manner; G, an elongated slot in the sliding hound B; H, a corresponding slot in the pole A; I, a slot in the sliding hound C. (Not shown in the drawings.)

J is the draft bolt or pin passing through said slots and firmly secured to the stationary hounds D and E.

K is a plate bolted to the upper side of the pole A, and provided with an upright pin, L, to receive the arms M and N, which pass through staples m n secured to the stationary hounds D and E, the outer ends of which, O and P, receive the side rods, Q and R, the other ends being secured to the cross brake-bar S, which carries the brakes or rubbers T and U which bear against the forward wheels.

Z is an eyebolt or pin which is inserted before the draft-pin J through the pole, thereby preventing the brakes or rubbers T and U from acting. The arms M N can be easily removed by taking off the nut on the upright bolt or pin. L, W, and X are the projections forming steps on the rubbers or brakes T and U.

What I claim as my invention, and for which I desire to procure Letters Patent, is—

The sliding hounds and pole, when used in connection with the arms M N, and rods Q R, connected with the rubbers T U and eyebolt or pin Z, all arranged and combined as set forth, and for the purposes specified.

ERASMUS BENNETT.
